UNITED STATES PATENT OFFICE.

SAMUEL CAME, OF HUNTINGTON, MASSACHUSETTS, ASSIGNOR TO CROMPTON & KNOWLES LOOM WORKS, OF WORCESTER, MASSACHUSETTS, A CORPORATION OF MASSACHUSETTS.

FILLING STOP MOTION FOR LOOMS.

Application filed November 2, 1925. Serial No. 66,132.

This invention relates to filling stop motions for looms and it is the general object of the invention to provide such a motion located approximately at the center of the 5 loom and connected by a minimum number of parts to the shedding mechanism of the loom.

When center stop motions have heretofore been applied to the Knowles type of loom to 10 which my invention more particularly relates it has been customary to provide an upright rod normally locked in down position but released by the stop motion to move upwardly under action of a spring to effect 15 stopping of the loom. The releasing of this rod is effected by giving it a slight lateral movement by mechanism controlled by the filling fork motion and it is a more particular object of my invention to simplify and 20 strengthen this intermediate mechanism to the end that the same may be more dependable and require less attention.

It is a further object of my invention to alter one of the parts of the commonly used 25 stop motion so that the control lever will be moved by direct engagement with the actuated lever to move in a plane parallel to the force which must be exerted to release the aforesaid upright rod.

30 It is a still further object of my invention to provide a motion so constructed that by a very slight adjustment the same parts may be employed for either a right or a left hand loom.

35 With these and other objects in view which will appear as the description proceeds my invention resides in the combination and arrangement of parts hereinafter described and set forth in the claims.

40 In the accompanying drawings wherein I have shown a convenient embodiment of my invention,

Fig. 1 is a vertical section taken through a portion of a loom and showing my improved stop motion applied thereto,

Fig. 2 is a vertical section on line 2—2 of Fig. 1 showing the parts in normal running position,

Fig. 3 is a view similar to Fig. 2 showing 50 the parts in knocking off position.

Fig. 4 is a top plan view looking in the direction of arrow 4, Fig. 2, showing the knocking off mechanism, and

Fig. 5 is a fragmentary side elevation looking in the direction of arrow 5, Fig. 4, 55 parts being broken away for the sake of clearness.

Referring to the drawings it will be seen that I have provided a breast beam 10 to the rear face of which is secured a bracket 11 held to the breast beam in fixed position by bolts 12. Said bracket extends downwardly from the breast beam and has a horizontal rearwardly extending arm 13 from the lower end of which extends a finger 14. Said arm 13 has secured thereto as by means of bolt 15 a cam plate 16 having a substantially horizontal run 17 and an inclined cam face 18. A stud 19 secured in finger 14 has pivotally mounted thereon an actuating lever 20 the upper end of which extends above the top of the arm 13 and is positioned as to its rearward movement by a laterally projecting lug 21 integral with said arm 13.

The lay 22 has secured to the under side 75 thereof a stand 23 on which is pivotally mounted a dagger support 24 from the forward end of which extends a dagger 25. The lower end of a rod 26 is pivotally connected to the dagger support 24 and the upper end 80 thereof is connected to an arm 27 rigid with a tine frame 28 which supports tines 29 forming the detecting element of the stop motion. The lay is provided with a transverse slot 30 which is positioned to receive 85 the tines when weft is absent.

As the lay advances the dagger 25 moves 90 first along the run 17 and then down the incline 18. This descent of the dagger is accomplished by a lowering of the tines and if weft has been laid by the shuttle S the tines will be held against moving into the slot 30, thus holding the dagger 25 above the rear 95 end of actuating lever 20 and as the lay continues to move forwardly said dagger will leave lever 20 unmoved. Should the shuttle S fail to lay filling, however, the dagger 25 will move all the way down incline 18 and as the lay continues to advance said dagger will engage the lever 20 and swing 100 the same about stud 19. The lever 20 is limited in its downward motion by a stop 31 cast integral with finger 14. This portion 105 of the mechanism is substantially the same as that shown in patent to Hutchins, No. 560,036, granted May 12, 1896.

As previously stated the invention relates more particularly to the type of loom having an upright locking bar which is held locked in down position when the loom is running. This portion of the mechanism is shown in Figs. 4 and 5 where it will be seen that the breast beam 10 has projecting rearwardly and laterally from one end thereof a stand 40 having a vertical slot 41 extending through the rear arm 42 thereof to receive the upper end of a locking bar 43. Said stand 40 is provided with a tooth 44 proportioned to enter a notch 45 formed in the forward face of the bar 43. A light leaf spring 46 is secured to the bar as at 47 and extends through the slot 41 to hold the bar toward the tooth 44.

The upper face of the stand 40 has secured thereto a stud 48 which forms a pivot for a link 49 loosely mounted thereon. Said link has pivotal connection as at 50 with a rod head 51 having a rear face 52 adapted to engage the forward upper part of the locking bar 43. A rod 53 secured to head 51 extends toward the central portion of the stop motion and has secured thereto a collar 54 between which and a fixed stand 55 extends a compression spring 56 the purpose of which is to hold the rod head to the right as shown in Fig. 4. Under normal running conditions tooth 44 will be received in notch 45 to prevent upward movement of the bar 43 but when a fault in the filling occurs rod 53 will be moved to the left as shown in Fig. 35 to swing the rod head 51 rearwardly around the stud 48 as a center. The head 51 will thereupon engage bar 43 and move it away from tooth 44 so that said bar will spring upwardly by mechanism not shown and stop the loom. The matter described in connection with Figs. 4 and 5 is substantially the same as shown in patent to Ryon, No. 1,509,614 issued Sept. 23, 1924.

My invention relates more particularly to the intermediate connections between the dagger actuated mechanism shown in Fig. 1 and the loom stopping mechanism shown in Figs. 4 and 5. Referring to Figs. 1, 2 and 3 it will be seen that I have formed the bracket 11 with a laterally extending arm 60 to which is pivotally connected as at 61 a vertical control lever 62 the upper end of which is connected as at 63 to the inner end of rod 53. The lower end of said vertical control lever 62 has a rolling surface 65 operatively positioned for direct engagement with one of two cam faces 66 or 67 carried by a forwardly extending leg 68 cast integral with the lever 20.

The parts are in the position shown in Fig. 2 when the loom is running normally with lever 20 held to the right as shown in Fig. 1 by the pressure of spring 56 which acting through the rod 53 holds upright lever 62 as shown in Fig. 2 and holds lever 20

against lug 21. When filling is absent lever 20 will be given a counterclockwise motion from the position shown in Fig. 1 the result of which will be to move the leg 68 down causing cam face 66 to move lever 62 so as to pull on rod 53. This in turn moves the rod head 51 to the left to unseat bar 43, a condition which as previously described results in the stopping of the loom.

The arm 60 is seen to be provided with a hole 69 which may be occupied by stud 61 when it is desired to have cam face 67 cooperate with lever 62. Under the latter conditions rod 53 would extend to the left and the mechanism shown in Figs. 4 and 5 would be located at the left hand side of the loom. The hole 69 is so located that the intersection of the cam faces 66 and 67 is approximately half way between the two positions which can be occupied by the stud 61.

For the sake of clearness I have omitted from Fig. 1 the usual form of guard which permits the loom to be started up after a filling break without a second stopping of the loom on the first pick. Although I have shown the form of stopping set forth in Patent No. 1,509,614, yet I do not wish to be limited to this particular construction.

In Patent No. 1,369,417 to Gagnon there is shown a control lever attached to the actuating lever by an intermediate connector which in practice has been found to stretch objectionably. As shown herein the actuating and control levers are in direct engagement and therefore are not subject to the defect mentioned in connection with the Gagnon device. Also, if the connector to the upright bar of the Gagnon patent were to extend in the opposite direction it would be pushed instead of pulled and therefore could not be used on an opposite hand loom. With the cam faces 66 and 67 as shown herein, however, the control lever will be effective to pull on the connector to the upright bar irrespective of the hand of the loom to which it is applied.

From the foregoing it will be seen that I have provided the usual actuating lever with cam faces which extend obliquely with respect to the plane of action of the lever and operate at the breaking of the weft thread to move the control lever 62 in a plane substantially parallel to rod 53. It will also be noted that the single spring 56 operates to hold the head 51 in normal running position and at the same time serves to hold the roll 65 near the bottom of the associated cam face so as to hold the actuating lever 20 against the lug 21. It will furthermore be noted that the said actuating lever has the cam faces thereof so disposed that the motion may by a very simple alteration be used either for a right or a left hand loom.

Having thus described my invention it will be apparent that changes and modifications

may be made therein by those skilled in the art without departing from the spirit and scope of the invention, and I do not wish to be limited to the details herein disclosed but 5 what I claim is:

1. In a filling stop motion for a loom having a bar normally locked when the loom is running, an actuating lever pivoted about a fixed center, means rigid with the actuating 10 lever defining a cam face extending obliquely with respect to the plane of action of said actuating lever, a control lever movable about a fixed center and having direct engagement with the cam face, and connections 15 between the control lever and the normally locked bar to move the latter to unlocking position when the actuating lever is moved.
2. In a filling stop motion for a loom having a fixed bracket and a bar normally locked 20 when the loom is running, an actuating lever pivoted to the bracket, a cam carried by the actuating lever and having a face extending obliquely with respect to the plane in which the actuating lever moves, a control lever piv- 25 oted to the bracket and movable by direct contact with the cam when the latter moves, and connections between said control lever and the normally locked bar to move the latter to unlocking position when the actuating 30 lever is moved.
3. In a filling stop motion for a loom having a fixed bracket and a bar normally locked when the loom is running, an actuating lever pivoted to the bracket and having a cam 35 face extending obliquely with respect to the plane in which said actuating lever moves, a control lever pivoted to the bracket and having direct operative connection with one 40 end of the cam face when the actuating lever is in normal position, and connections between the control lever and the normally locked bar to move the latter to unlocking position when said actuating lever moves to cause relative motion of the cam face and 45 control lever.
4. In a filling stop motion for a loom having a bar normally locked when the loom is running, an actuating lever movable about a fixed pivot, a cam face on said actuating 50 lever extending obliquely with respect to the plane in which the said lever moves, a control lever movable about a fixed pivot

and having direct engagement with the cam face, connections extending between the control lever and the normally locked bar to 55 move the latter to unlocking position when the actuating lever is moved to cause oscillation of the control lever by means of the cam face, and yielding means acting through the connections to hold said control lever 60 against the cam face to hold said actuating lever in normal position.

5. In a filling stop motion for looms, an actuating lever movable about a fixed center, a pair of oppositely disposed cam faces on 65 said lever lying on opposite sides of a plane passing between them and parallel to the plane in which the actuating lever moves, a control lever, and a support for said control lever to mount the same in either of 70 two positions, said control lever having operative engagement with one cam face in one position and having operative engagement with the other cam face in the other position, said control lever receiving a loom 75 stopping movement when in either position when the actuating lever is moved.

6. In a filling stop motion for looms, an actuating lever movable about a fixed center, a pair of oppositely disposed cam faces on 80 said lever, a control lever and a support for said control lever to mount the same in either of two positions, said control lever having operative engagement with one cam face in one position and having operative engagement with the other cam face in the other position, said control lever receiving a loom 85 stopping movement when in either position when the actuating lever is moved.

7. An actuating lever for a loom filling 90 stop motion having a control lever to be oscillated and a bracket for supporting said actuating lever in two positions, said actuating lever having a pair of oppositely disposed cam faces extending obliquely with 95 respect to the plane in which the actuating lever moves when in position, either of said faces being effective to cooperate with the control lever to give the same a loom stopping motion.

In testimony whereof I have hereunto affixed my signature.

SAMUEL CAME.
